UNITED STATES PATENT OFFICE.

SIDNEY H. SONN, OF NEW YORK, N. Y.

CONTAINER.

Application filed June 24, 1924. Serial No. 721,998.

This invention relates to a box or hollow container and especially to a box which may be shipped in a knocked down condition and be easily re-assembled by inexperienced persons when desired and is more particularly directed to a box of the nature described and especially suitable to contain such articles as hats.

The principal object of this invention is to provide a box or hollow container of the nature described which may be shipped in a knocked down condition and which may be easily assembled by an inexperienced person when desired, which in the knocked down condition will be extremely compact and which will thus be a space saver and which may be manufactured of such materials and by such process as will enable the finished article to be sold at a comparatively low cost.

A further object of the invention is to provide a hollow container of the nature described which will when assembled be of a shape most desired by dealers, especially in millinery.

Other objects and advantages of the invention will appear as the description of the particular physical embodiment selected to illustrate the invention progresses, and the novel features of the invention will be particularly pointed out in the appended claims.

In describing the invention in detail and the particular physical embodiment selected to illustrate the invention, reference is had to the accompanying drawing, wherein I have illustrated a particular preferred physical embodiment of my invention, and wherein like characters of reference designate corresponding parts throughout the several views, and in which:

Figure 1 is a perspective view of a box or container embodying my invention; Fig. 2, is a side elevational view, partly in section, of the box shown by Fig. 1; Fig. 3, is a top plan view of the cover and attaching means of my box shown by Fig. 1; Fig. 4, is a plan view of the bottom and side when laid flat as employed in my box; Fig. 5, is a cross sectional view of the sides and bottom of my box, obtained by forming the material shown by Fig. 4, before the top and attaching means are connected; Fig. 6, is a cross sectional view on the plane indicated by the line VI—VI of Fig. 5 viewed in the

direction of the arrows at the ends of the line.

It is realized by those acquainted with such businesses, as the hat trade, and especially ladies' hats, that it is very desirable and in fact practically necessary for shops selling hats to provide a box in which a hat, such as a lady's hat, may be carried from the store in such a way that it will not be injured or exposed to view. It is also well known that hats, especially ladies' hats, are often of large size and of a somewhat fragile nature so that the box or container within which they must be placed must be of a relatively large size and relatively strong so, at least, to resist deformation by any of the ordinary blows and shocks which might be encountered in transporting such a box in crowded localities such as department stores or crowded elevated or subway trains. It is also well known that many of the better quality ladies' millinery shops are, in large cities, of no great dimensions and space is extremely valuable and limited so that there is very often no available space in which to properly store any sufficient number of hollow containers or boxes with which to supply customers making purchases.

Applicant has attempted to overcome the difficulties inherent in present date practices by providing a container or box which may be stored in a knocked down condition so that it will occupy, relatively, a very small space, to the end that the class of shops above mentioned may readily keep several hundred of these knocked down containers on a shelf or in a draw and so be prepared for the most extreme demands which may be made upon them for containers and at the same time be able to purchase these containers at a more reasonable price, by reason of the large quantity bought at one time, and so protect themselves against any chance of exhausting their stock of containers by reason of a brisk trade and be further freed from the necessity of paying high rent for space in which to store a relatively small number of an exceedingly bulky group of ordinary containers.

My improved box or container in general outline is shown by Fig. 1. It is the general form of a hollow right cylinder with a flattened side. This flattened side 1 is useful in that the box may be rested thereon with no fear that it will roll. This flattened

side is positioned diametrically opposite the carrying handle 2, so that the box is naturally rested on the flattened side when it is deposited. The box has a liftable pivoted 5 cover 3, which may be fastened, so that it will not fly open when being carried, by flexible latch 4 engaged over the curved up end of the carrying handle 2.

The side wall of my box is composed of 10 the rectangular sheet 5, Fig. 4. This rectangular sheet has an upturned edge 6, which forms a ledge against which the bottom rests when the box is assembled, as will more fully appear hereinafter. The sheet 15 5 is scored along the line 7 and also along the line 8 so that when the sheet is formed the portion from 7 to 9 and from 8 to 10 will form a chord as appears in Fig. 6, the ends 9 and 10 abutting.

20 Near one end of the sheet 5, I attach a bottom or end wall 11, circular in outline, except along the line 12, which is a chord corresponding to the chord formed in the side by the portions 7 to 9 and 8 to 10, as 25 appears in Fig. 6. The material set off by the chord, that is, that embraced between lines 12 and 13 of Fig. 4, constitutes a turned down portion when the box is completed. This turned down portion serves to attach, 30 as by the use of an adhesive, the bottom 11 and the side 5. The portion 14 to 15 of the turned down portion of the bottom extends, as shown in Fig. 4, beyond the edge 10. This extension from 14 to 15 is of the same magnitude as the magnitude of the strip from 35 7 to 9, and is preferably no greater than is necessary to properly hold and contain fasteners, as 16 and 17. The turned down portion between 12 and 13 serves to hold the bottom 11 to the side 5 and so the portion 14 to 15 is made as small as possible in order to have as large a portion as possible fastened 40 to the side 5 by an adhesive.

If bottom 11 is placed at a right angle to 45 sheet 5 and then sheet 5 curled about the bottom 11, the parts will take the position as shown in Fig. 6. The bottom 11 will rest on the ledge 6 and in order to prevent the bottom 11 from being displaced I have attached 50 a stop piece 18 projecting from the side wall 5, positioned about the thickness of the bottom 11 from the upper edge of ledge 6. This construction, with the parts in place is well shown by Fig. 5.

55 The cover of the box is shown in Fig. 3 in plan and in Fig. 2 in section. It consists of a flat piece 19 formed with a surrounding flange 20. To the flat side 21 of the flange 20 is attached, as by an adhesive, the cover attaching flap and side wall connector 22. This flap 22 is, in the form shown, rectangular and its free portion, that is, from the scoring 23 downwardly, as shown in Fig. 2, is of the same superficial dimensions as the 60 flattened side 1 of the box. This flap 22 car-

ries a plurality of fasteners, in this case four, 24, 25, 26 and 27. In my preferred form, shown in the drawings, these are ordinary "snap" fasteners composed of a male and female member. The female member is placed 70 in position on the flap 22. Corresponding male members 16, 17, 28 and 29 are placed on the flat side of the side wall 5, part being positioned on the portion from 7 to 9 and part on the portion from 8 to 10. When the 75 fasteners are snapped together the cover is attached and the abutting free ends of the side wall 5 are held firmly abutting as at 9 and 10, Fig. 6. The disposition of the assembled parts including flap 22 is well shown in 80 Fig. 2.

In order to provide means for carrying and latching the cover of the box, I provide 85 a handle 2, attached in any suitable or appropriate manner to the side wall 5. One end of the handle 2, is preferably formed into a partial loop, 30, Fig. 2 and Fig. 1. Attached in any suitable or preferred manner to cover 10 is a flexible latch 4. This latch is formed with an orifice 31. When the loop 90 30 is entered in the orifice 31, as may be readily done after closing the cover, the latch then holds the cover from flying open while the box is being carried.

95 From the description hereinbefore given it will be apparent that I have devised a box or container which may be shipped in the knocked down condition, that is, with the side wall 5 and bottom 11 flat and parallel one to the other and with flap 22 extended, as shown in Fig. 3. In this condition the box will occupy relatively little space. The box is easily assembled, requiring little or no skill and when assembled provides a box 100 which is relatively strong and will resist deformation by the usual forces to which such a box is subjected when in use.

105 Although I have particularly described the construction of one physical embodiment of my invention and explained the operation and principle thereof, nevertheless, I desire to have it understood that the form selected is merely illustrative but does not exhaust the possible physical embodiments of the idea of means underlying my invention.

110 What I claim as new and desire to secure by Letters Patent of the United States, is:

1. A hollow container including a side wall formed with spaced projections and abutting ends; an end wall attached to the side wall and held between the spaced projections; a flanged cover; a flap attached to the flange of the cover and covering the abutting ends and means removably attaching the flap to each of the abutting ends of the 115 side wall.

120 2. A hollow container including an end wall; a side wall and a cover, the side wall curled about the end wall and bearing projections between which the end wall is held 130

and the ends of the side wall abutting and being formed flat for a short distance; a flap attached to the cover and covering the flat portion of the side wall and means attaching the flap to the ends of the side wall whereby the side wall is held in place and a hinge is provided for the cover.

5 3. A hollow container including an end

wall and a side wall wrapped about the periphery of the end wall and a sheet of material positioned along side of the side wall and overlapping the abutting ends thereof and cooperating fasteners in each of the ends of the side wall and in the said sheet.

10
